O. SCHÜTZ,

APPARATUS FOR MIXING AND DISTRIBUTING LIQUIDS.
APPLICATION FILED FEB. 9, 1916.

1,208,670.

Patented Dec. 12, 1916.

Diagram 'a' shows a double-walled tube with a central channel 'f'. The tube has a height 'h' and a width 'c'. It is supported by a zigzag spring at the bottom. The left end is labeled 'on d' and the right end is labeled 'o'.

UNITED STATES PATENT OFFICE.

OTTO SCHUTZ, OF NEW YORK, N. Y., ASSIGNOR TO BADISCHE COMPANY, OF NEW YORK,
N. Y., A CORPORATION OF NEW YORK.

APPARATUS FOR MIXING AND DISTRIBUTING LIQUIDS.

1,208,670.

Specification of Letters Patent. Patented Dec. 12, 1916.

Application filed February 9, 1916. Serial No. 77,342.

To all whom it may concern:

Be it known that I, Otto Schutz, a citizen of the United States, residing at New York, county of New York, and State of New York, have invented new and useful Improvements in Apparatus for Mixing and Distributing Liquids, of which the following is a specification.

This invention relates to an apparatus for distributing a solution, and it includes a tank having a plurality of compartments for thoroughly and evenly saturating a substance with a fluid, and capillary means for drawing minute quantities of the fluid from the tank.

The object of the invention is to provide the tank with a series of partitions of less height than the outer walls, forming a number of passages, so that when a concentrated acid solution or powder is placed in a compartment it will be thoroughly diluted before it overflows into the last compartment where it is drawn off.

The invention is more fully described in the following specification and claims and illustrated in the accompanying drawings in which:

Figure 1 represents a plan view of an apparatus embodying this invention showing some of the parts removed. Fig. 2 is a transverse section of the same on a larger scale. Fig. 3 is a front elevation of Fig. 2.

In this drawing the letter *a* designates a tank which is preferably constructed of wood, suitable to hold a liquid, and can be lined with an acid resisting substance. The walls of the tank are fastened together by means of brass screws *b* best seen in Fig. 3. A number of longitudinal partitions *c* and *d* divide the interior of the tank into a plurality of compartments *e*, *f* and *g*. The compartments *e* and *f* respectively communicate with each other by openings *h* located at each end of the partition *c*. The compartment *e* is adapted to receive the liquid introduced by a pipe *i* connected to a reservoir or other source of supply. The flow of the liquid into the compartment is controlled by a valve *j*.

The partitions *c* and *d* are respectively of smaller height than the rear wall of the tank as indicated in Fig. 2, so that when the solution reaches the top of the partition *d* it will flow over the partition into the succeeding compartment. The front longitudi-

dinal wall of the tank is also somewhat less in height than the rear wall but is preferably higher than the partitions as shown. The level of the liquid in the tank is normally slightly lower than the depth of the front wall. The front wall has secured to it a series of solution distributing lead tubes *k* each having an open front portion *m* extending over the top and down the inside of the front wall of the tank. The upper portion of each pipe is formed with a gutter or channel *n* the object of which will be hereinafter described.

A bar or beam *o* is mounted on the end walls of the tank and extends longitudinally along the top over one of the partitions. A series of wicks or other capillary devices *p* are suspended from holding devices *q* attached to the bar. Each branch of a wick as shown in Fig. 3, is suspended in the liquid and it is supported or guided in a gutter until it reaches over the top of the tank into the tube. The wick thus sucks a certain amount of the solution from the top of the liquid and by its capillary attraction it will conduct minute quantities of the liquid over the front wall of the tank and distribute or infuse it evenly into a mass of paper pulp or other material. The lower inner ends of the tubes are fastened air-tight to the inner side of the front wall as shown at *r* to prevent leakage of the acid between the joints of the gutters.

I claim:

1. An apparatus for mixing liquids comprising a tank adapted to contain a solution, and having a front wall of less height than its other walls, a plurality of partitions of less height than the front wall to divide the tank into a number of compartments, one partition having openings connecting adjacent compartments, capillary means arranged over the front wall and suspended into the liquid for drawing off minute quantities of the solution.

2. An apparatus for mixing liquids comprising a tank adapted to contain a solution, and having a longitudinal front wall of less height than its other walls, a plurality of longitudinal partitions of less height than the front wall to divide the tank into a number of compartments, one partition having an opening at each end connecting adjacent compartments, capillary means arranged over the front wall and suspended

into the liquid for drawing off minute quantities of solution.

3. An apparatus for mixing liquids comprising a tank adapted to contain a solution, and having a longitudinal front wall of less height than its other walls, a plurality of longitudinal partitions of less height than the front wall to divide the tank into a number of compartments, gutters provided 5 with tubes secured to the front wall, capillary means projecting into the tubes over the front wall from the gutter and suspended into the liquid for drawing off minute quantities of the solution.
- 15 4. An apparatus for mixing liquids comprising a tank adapted to contain a liquid solution, and having a front longitudinal wall of lower height than its other walls, a plurality of compartments located in the 20 tank, liquid distributing tubes including gutters secured to the front longitudinal wall, a bar arranged above the compart-

ments, capillary means suspended from the bar into the liquid and guided to the gutters into the tubes.

5. An apparatus for mixing liquids comprising a tank adapted to contain a solution, and having a front longitudinal wall of lower height than its other walls, a plurality of partitions of smaller height than the front wall for dividing the tank into a series of compartments, liquid distributing tubes provided with gutters disposed on the front longitudinal wall, a bar arranged above the compartments, capillary means suspended from the bar into the liquid and guided to the gutters into the tubes.

25 In testimony whereof I have hereunto set my hand in the presence of two subscribing witnesses.

OTTO SCHUTZ.
